ADVERTISING DISPLAY UNIT OR THE LIKE

John G. Schramm, 2564 N. 33rd St., Milwaukee, Wis.

Filed Nov. 10, 1964, Ser. No. 82,548

Term of patent 3½ years

(Cl. D1—12)

FIG. 1 is a perspective view of an advertising display unit or the like embodying my new design; and

FIG. 2 is a side elevational view thereof.

The rear and other side, not shown, are substantially plain.

I claim:

The ornamental design for an advertising display unit or the like, as shown and described.
